UNITED STATES PATENT OFFICE.

ANDRÉ BOIVIN, OF PARIS, FRANCE.

MACHINE FOR MANUFACTURING SUGAR LOAVES MOLDED BY COMPRESSION.

1,379,847.

Specification of Letters Patent. Patented May 31, 1921.

Application filed November 17, 1919. Serial No. 338,754.

To all whom it may concern:

Be it known that I, ANDRÉ BOIVIN, a citizen of the French Republic, residing at 145 Rue de Flandre, Paris, France, have invented certain new and useful Improvements in Machines for Manufacturing Sugar Loaves Molded by Compression, of which the following is a specification.

In the manufacture of ingots or blocks of sugar by compression great difficulties are met with when it is desired to obtain a block the height of which, in the direction of the compression, attains a certain importance with relation to the transverse dimensions (horizontal section).

When the compression is exerted upon the lateral walls of the mold considerable friction prevents the compression from transmitting itself through the sugar in the direction of the compression.

It happens in this case that the block of sugar is compressed to a considerable extent and very dense in the vicinity of the compressing piston but very little compressed or not at all in the middle.

In order to manufacture a sugar loaf by compression it is necessary to elude this difficulty.

Attempts have been made to meet this objection by constructing a truncated cylindrical mold in the cylindrical ends of which two compressing pistons acted.

Notwithstanding the improvement effected due to this procedure, the center of the loaf was still insufficiently compressed.

The machine which forms the subject matter of the present invention comprises a third compressing device, acting at the center and constituted by a truncated cylindrical socket or hollow piston by means of which it becomes possible to compress almost equally all parts of the sugar loaf.

The accompanying drawing represents by way of example a system of pistons constituting the essential feature of the invention and a machine arranged to set such a system of pistons in action.

Figure 1 is an axial section of the mold and of the system of pistons, these latter being shown in elevation.

Fig. 2 is an elevation of the machine.

Fig. 3 is a vertical section on the line 3—3 of Fig. 2.

Fig. 4 is an underneath plan view.

Fig. 5 is a partial vertical section on the line 5—5 of Fig. 4 on a larger scale.

Fig. 6 is a plan corresponding to Fig. 5.

Fig. 7 is a vertical section of a modification of the mold with hollow piston.

Fig. 8 is a vertical section on the line 8—8 of Fig. 2.

Fig. 9 is a vertical section of the feeding hopper on a larger scale.

Fig. 10 is a plan view of the same hopper, with the closing flaps separated.

Fig. 11 is a partial horizontal section on the line 11—11 of Fig. 8 showing the device for expelling the molded pieces.

In Fig. 1, 2 denotes the hollow piston which is cylindrical externally and of truncated cylindrical form internally.

It slides in the mold 3 which is cylindrical at the top and truncated in the middle then cylindrical again at the lower part in which the piston 1 slides.

The following is the order of the operations:

The large lower or bottom piston 1 being at the bottom of the lower opening of the mold 3 and the hollow piston 2 at the top of its stroke the mold 3 is filled with sugar in grains and moistened to the desired point through the opening 22.

The small upper piston 4 then descends and enters a short distance into the cylindrical hollow part of the hollow piston, slightly compressing the sugar, then this small piston continues its stroke carrying with it the hollow piston 2. By reason of the truncated form of this latter, the sugar which it contains becomes compressed laterally, and acts afterward itself as a rigid and solid piston against the sugar which is situated lower down in the fixed truncated part of the mold 3.

During this time, the large lower piston 1 rises compressing the sugar from the bottom upward.

When the truncated surfaces of the hollow piston and of the mold are in line with and

form an extension of each other, the hollow piston is stopped in its stroke.

The small solid piston continues to descend and effects the compression of the 5 upper part of the sugar loaf.

When this compression is completed the small and large pistons stop.

If the ratios of the volumes before and 10 after compression have been properly calculated, the sugar loaf ought to be solid from top to bottom and only present acceptable differences of density.

Removal from the mold is effected as follows:—

15 The small piston 4 and the hollow piston 2 descend simultaneously while the large piston 1 descends likewise with an identical speed.

It follows that the compressed sugar loaf 20 detaches itself from the truncated fixed part of the mold. These movements continue until the base of the sugar loaf has reached the cylindrical lower part of the mold 3. At this moment the hollow piston 2 stops.

25 The small piston 4 continues to descend, and also the large piston 1 until the small piston has slightly moved beyond the hollow cylindrical part of the hollow piston.

At this moment the sugar loaf is detached 30 from the side walls of the mold.

The small piston stops and rises again, and the large piston which carries the sugar loaf continues to descend until the top of the sugar loaf is disengaged from the 35 interior of the mold.

At this moment the sugar loaf is thrust horizontally on to a table the surface of which is flush with the base of the large piston.

40 The machine represented in Figs. 2 to 4 is constructed to realize mechanically the above operations. It is constituted in the following manner.

A circular plate 5 movable about a vertical pivot 6 carries four molds like the one 45 above described. It is driven around by a ratchet 7, lever 8, slide 9 and crank 10 system constructed so as to stop after each quarter of a revolution.

50 During each stoppage the following operations take place simultaneously:—

1. At the filling station A a double gate 11 (Figs. 9 and 10) opens and allows the sugar contained in a hopper 39 to fall into 55 the mold, the two flaps are made to co-act by means of toothed sectors 11^a, and one of these is actuated by a cam 60 through the medium of a lever 61, a link 62 and an arm 63. Within the hopper are disposed the rotary stirring members 64 serving to facilitate the descent of the sugar when the flaps 60 are open. The stirring members are made to co-act by the pinions 64^a and one of these is actuated by a driving pulley 65 by means

of belt 66 passing around a second pulley 67 65 secured to the shaft 68 of the said stirring member.

The lower part of the mold would be open (as the compressing pistons do not follow the circular plate in its rotation) if there 70 were not at this filling station a special piston 12 which enters into the lower opening of the mold.

The hollow piston 12 is slidable along a fixed rod 69 and is pivoted to the end of a 75 lever 70 the opposite end whereof is given a rapid reciprocating motion by means of an eccentric 43 and an eccentric rod 51. At an intermediate point, the lever 70 is pivoted to another eccentric rod 40 which engages an eccentric 71 movable about a stationary shaft 72. At each revolution of the shaft 73 of the main cams, the eccentric 71 is given a swinging motion through the medium of a cam 74, a lever 42, and a link 80 41 and a lever 75 secured to the eccentric. During the period of rotation of the disk 5, the eccentric 71 is lowered in such a manner that the vertical movement of the piston 12 produced by the eccentric 43 occurs 90 entirely below the said disk. Inversely, when the disk reaches one of its stopping positions, the eccentric 71 raises the lever 70 whereby the piston 12 is raised within the mold which has been brought above the 95 latter and effects a reciprocating motion in the interior of the mold. This movement produces two results. The first is that of compressing the sugar which falls into the mold, the second that of forming at the end 100 a veritable plug of sugar compressed into the lower part of the mold, which plug keeps in all the sugar contained above it in the mold.

The piston 12 is lowered below the disk 105 5 and the double gate 11 closes again before the commencement of the quarter revolution of this plate.

2. At the waiting station B which succeeds the filling station A no operation takes 110 place.

3. At the station C are situated the compressing pistons 1, 2, 4 and it is here that the operations of compression and removal from the molds take place.

4. At the station D the cleaning out of 115 the mold is effected.

The small compressing piston 4 is rigidly attached to a cross bar 13 sliding in two guides 14 and connected to two connecting 120 rods 15 which are operated by two levers 16 and two symmetrical cams 17.

The lower compressing piston 1 is rigidly attached to a slide 18 connected to the connecting rod 19, the lever 20 and the central 125 cam 21.

For the operation of the hollow piston 2 this latter carries two stirrup lugs 22 which

can be lifted up by two catches 23 rigidly attached to the cross bar 13. These catches produce the movement from below upward.

For the movements from the top downward, two thrust bars 24 rigidly connected momentarily to the cross bar, bear on the two stirrup lugs of the hollow piston.

To this end the thrust bars 24 are adapted to slide freely in seats made in the cross bar. Their stroke in a downward direction is limited by two stops 25. At the upper part of the cross bar is an oscillating circular bolt 26 operated by the system of levers 27, 28, 29, 30, 31, 32 and the cam 33 and capable of occupying three positions. In the position in which it is inoperative this bolt allows the thrust bars to rise completely into their recesses. This position corresponds to the second phase of removal from the mold.

In the completely locked position the bolt rigidly secures the thrust bars to the cross bar. This position corresponds to the first phase of the compression when the hollow piston has to produce its compressing operation.

The third position is the one which permits the thrust bars to slide to a certain extent upward in the cross bar. This sliding movement is produced in the second phase of the compression when it is the small solid piston which effects its compressing operation, the hollow piston remaining stationary.

It is likewise the position of the bolt which corresponds to the first phase of removal from the mold which immediately succeeds the second phase of compression, and during which the solid piston and the hollow piston act simultaneously to remove the sugar loaf from the mold.

In order to fulfil the functions above described the bolt 26 has for the two stages figured in the drawing recesses or hollows 34. The cam which works it brings above the thrust bars the desired stage at the opportune moment.

The crank 28 which works the connecting rod of the bolt slides along the intermediate shaft 29 and is carried along in a long groove 50 by a cotter pin so that the bolt is operated whatever be the position occupied by the cross bar.

When the two phases of the compression are completed the operation of removal from the mold commences. In order to carry out this operation the lower compressing piston has to rigorously make the same stroke as the upper compressing piston.

In order to carry out this function the lower piston ceases to be operated by the cam 21 and its lever 20 and receives its movement from the cross bar 13.

To this end the two connecting rods 15 which operate this cross bar carry two driv-

ing nuts 35 which, at the desired moment, 65 drive the arms 36 rigidly attached to the slide 18 carrying the lower compressing piston 1.

These arms 36 serve likewise to maintain in equilibrium the system of the slide, piston, connecting rod and large lever with the roller, by means of two counterweighted cables 37 with return rollers 38 (which are balanced by the counterweights 76) which it is necessary to utilize since the system is 75 released by the cam and must not drop under the action of its own weight. The cessation of the driving action of the cam is obtained by providing play on the faces of this cam so that the rollers no longer bear 80 thereon.

After the sugar loaf has been removed from the mold the cross bar resumes and maintains its raised position and in consequence thereof the catches 23 cause replacement of the hollow piston 2 in its raised position which is that of filling.

The rotation of the plate brings the mold, which was at the station corresponding to the operations of compression and removal 90 from the mold, into the cleaning position. It is in reality useful to free the interior of the mold from the sugar adhering thereto and to slightly moisten the surfaces.

This result is obtained by means of a brush 95 77 of a suitable form, circular, on a vertical spindle 78 and having a rotary movement imparted to it about this spindle. This motion is obtained by a sprocket wheel 79 through the medium of a chain 80, another 100 wheel 81, a shaft 82 and the bevel gears 83, 84, this latter being keyed to the shaft 78 whereby the latter may rise and fall. During the rotation of the plate this brush is kept drawn down below the plate and is surrounded by a jacket of sheet iron (not shown) in the interior of which an atmosphere supersaturated with moisture is maintained by means of steam.

As soon as the rotation of the plate is completed the brush (always rotating) is raised by a lever 85 and cam 86 and enters into the interior of the sugar loaf mold, cleans it out, moistens it and resumes its position before a fresh rotation of the plate takes place. 115

The flat compressing surfaces of the compressing pistons 1 and 4 likewise require to be brushed. To this end the lower piston 1 is brushed at the time of the mechanical movement which expels the sugar loaf from 120 this piston after removal from the mold. The device which expels the sugar loaf is an ejector 44 the mechanism of which is represented in Figs. 8 and 11. This ejector 44 is held by a slide 87 which slides in a horizontal guide 88 and is worked by a connecting rod 89, lever 90 and cam 86^a secured to the cam 86. This ejector acts on the lower part

of the sugar loaf, and has the form of a semitruncated cone so as to bear well against the sugar loaf.

It carries at the rear a brush 45 which, 5 during the horizontal movement of the ejector, cleans the upper surface of the piston 1.

The cleaning of the piston 4 is effected by a special mechanism. A brush 46 is carried by a lever 47 which is operated by a system 10 of levers 48, connecting rods 49 and cams 50. This system comes into action to brush the moment the cross bar 13 reaches its upper position before it redescends.

The quantity of sugar to be introduced 15 into the mold can be regulated in the following manner:—

The weight of the sugar introduced into the mold at the filling station can be varied by modifying the position of the compressing 20 piston 12. It has been seen that on the stoppage of the plate, this piston, which has a slight continuous rising and falling movement imparted to it enters into the mold. The extent to which this piston can enter 25 into the mold can be regulated by lengthening or shortening the connecting rod 51 by means of a swivel 52. These variations modify the volume left available for the sugar, otherwise called the capacity of the 30 mold.

Fig. 7 shows an arrangement which allows the hollow piston 2 to remain in the positions in which it is placed by the catches 23 and the thrust bars 24. This piston 35 carries below its lugs 53 two cylindrical rods 54, rigidly connected to these lugs and sliding in two adjustable brakes 55. The friction of the brakes is so regulated as to balance the weight of the hollow piston 2.

40 What I claim and desire to secure by Letters Patent of the United States is:—

1. In a machine for manufacturing by compression sugar loaves or compressing any other material capable of being molded, 45 the combination of a mold of cylindrical truncated cone shape, at least one hollow cylindrical truncated cone shaped compressing piston adapted to slide in the interior of the said mold and two solid compressing 50 pistons adapted to slide respectively in this piston and in the mold.

2. In a machine for manufacturing by compression sugar loaves or compressing any other material capable of being molded, 55 the combination of a horizontal revolving plate, several molds of cylindrical truncated shape at right angles to this plate, a like number of hollow compressing pistons sliding in these molds and a double number of 60 solid compressing pistons sliding respec-

tively in the said molds and the said hollow pistons, means for filling the molds from the top at a point of the revolution of the said plate, means for moving the compressing pistons at another point of the revolution and means for extracting from the mold the loaf of material molded at a third point of the revolution of the plate.

3. In a machine for manufacturing by compression sugar loaves or compressing 70 other material capable of being molded, the combination of a horizontal revolving plate, several molds of cylindrical truncated shape at right angles to this plate, a like number of hollow compressing pistons sliding in 75 these molds and a double number of solid compressing pistons sliding respectively in the said molds and the said hollow pistons, means for filling the molds at the top at a point of the revolution of the said plate, a 80 piston adapted to engage the lower part of one of the molds at this same point, and means for moving this latter piston during the filling in order to retain and ram into the mold the lower layers of the material 85 introduced, this latter piston not rotating with the plate.

4. In a machine for manufacturing by compression sugar loaves or compressing any other material capable of being molded, the 90 combination of a cylindrical truncated mold, at least one hollow compressing piston of cylindrical truncated shape adapted to slide in the interior of the said mold and two solid compressing pistons adapted to 95 slide respectively in this hollow piston and in this mold, operating means for moving the different pistons mentioned, these means being adapted to produce, at the time of the molding, first the descent of the upper compressing piston and its entrance into the hollow cylindrical part of the hollow piston and then the carrying along of the hollow piston by the upper piston, and afterward the descent of the upper piston into the 100 hollow piston which has become stationary, at the same time as the ascent of the lower piston and at the time of removal from the mold, the simultaneous descent of the upper piston of the hollow piston and of the 105 lower piston, then the stoppage of the hollow piston, the two others continuing their movement, and finally the descent of the lower piston alone.

In testimony whereof I affix my signature 115 in presence of two witnesses.

ANDRÉ BOIVIN.
